(57) **CLAIM**

The ornamental design for a handle for push-pull valve assembly, as shown and described.

DESCRIPTION

FIG. 1 is a front perspective view of a first embodiment; FIG. 2 is a front perspective view of a second embodiment having an extended distal end section; FIG. 3 is a left side elevation view of the embodiment of FIGS. 1 and 2; FIG. 4 is a right side elevation view of the embodiments of FIGS. 1 and 2; FIG. 5 is a front elevation view of the embodiment of FIG. 1; and, FIG. 6 is a front elevation view of the embodiment of FIG. 2. The rear elevation view, the top plan view and the bottom plan view of the embodiment of FIG. 1 are the same as FIG. 5. The broken lines form no part of the claimed design.
